UNITED STATES PATENT OFFICE

SHERMAN O. HUFFMAN, OF DUQUESNE, PENNSYLVANIA

LEADER CARRIER

Application filed March 19, 1929. Serial No. 348,267.

This invention relates to the class of receptacles and pertains particularly to an improved type of fly and leader carrier for the use of fishermen.

5 The primary object of the present invention is to provide a leader carrier of a type designed to keep moist over a long period of time so that gut leaders may be kept soft and pliable.

10 Another object of the invention is to provide a leader carrying receptacle which may be kept moist for a long period and which may, at the same time, be conveniently carried in the pocket without danger of the 15 moisture from the receptacle being absorbed by the clothing of the carrier.

Still another object of the invention is to provide a leader carrier designed to provide an air sack which may be filled with air when 20 the receptacle is in use and which will act to prevent the receptacle from sinking in the event that it falls into the water.

The invention will be best understood from a consideration of the following detailed description taken in connection with the accompanying drawing forming a part of the present invention with the understanding, however, that the invention is not confined to any strict conformity with the showing of the 25 drawing but may be changed or modified so long as such changes or modifications mark no material departure from the salient features of the invention as expressed in the appended claims.

30 In the drawings:—

Figure 1 is a view in side elevation of the leader carrier embodying the present invention showing the inner receptacle thereof partly withdrawn from the waterproof outer 40 receptacle.

Figure 2 is a longitudinal sectional view taken upon the line 2—2 of Figure 1.

Figure 3 is a view in cross section of the 45 receptacle taken upon the line 3—3 of Figure 1.

Referring to the drawing in detail wherein like numerals of reference indicate corresponding parts throughout the several views, 50 the numeral 1 indicates generally the inner

receptacle while the numeral 2 indicates generally the outer receptacle.

The inner receptacle 1 is in the form of a two compartment purse which has a mouth frame 3 made up of a central unit and two side or outer units indicated by the numerals 4 and 5 respectively which units are of substantially U-shaped formation and have their ends hingedly connected together as indicated at 6. The units 4 and 5, as shown, are 55 designed to be arranged in side by side relation and to each of the pivot pins 6 of the top frame is pivotally attached the free end of one side leg of a lower upright U shaped frame 7.

Within and between the frames 3 and 7 is a bag 8 formed of chamois skin, the bag being centrally divided by a wall of the same material as indicated at 9 to form the two compartments or pockets 10. As shown, the top 70 edges of the side walls of the bag are each connected to one of the outer frames 5 while the top edge of the central wall 9 is connected to the frame 4 and in addition is connected at its side and bottom edges to the edge and 75 bottom walls of the bag. The bag 8 at its sides and bottom may be secured in any suitable manner to the outer frame 7.

The receptacle 2 which is preferably of rubber or rubberized material is in the form of an open mouthed pouch into the mouth of which the purse or inner receptacle 1 may be extended, as shown in Figures 1 and 2. One side wall of the outer receptacle or pouch 2 is provided with an air bag 11 through the 80 wall of which a suitable valve 12 opens by means of which air may be introduced into the bag as desired.

The opposite wall of the pouch 2 has secured thereto a pocket 13 the top of which is 85 normally open and may be covered by the flap 14 secured to the side wall of the pouch adjacent the top and adapted to be secured adjacent its lower end or edge by a suitable fastener, such for example, the glove snap 15. 90

By actual test it has been found that with a leader receptacle constructed in accordance with this invention the chamois walls of the pocket 8 when moistened will retain the moisture over a long period of time thereby 100

making it unnecessary to frequently rewet the leaders while they are being carried upon a fishing expedition. The leaders are easily obtainable when wanted and the receptacle as a whole is safe from loss in the event that it is accidentally dropped into the water because of the air bag 11 associated with the pouch 2.

Having thus described my invention, what I claim is:—

- 10 1. A fisherman's leader carrier comprising a purse consisting of a frame and a bag of moisture retaining material secured therein, a water proof pouch designed to receive the purse, and an air bag forming a part of said pouch to make the same non-sinkable.
- 15 2. A fisherman's leader carrying receptacle comprising a bag of moisture retaining material, a rigid frame surrounding the bag about the edges thereof, said bag having a mouth, means forming a part of said frame for securely closing the mouth, and a water proof receptacle designed to receive said frame and bag.
- 20 3. A fisherman's leader carrier comprising a purse having a frame and a bag of chamois skin, said bag having a mouth and said frame being formed to provide means for securing the bag mouth closed, and a pouch of water proof material designed to receive said purse.
- 25 4. A fisherman's leader carrier comprising a purse having a frame and a bag of chamois skin, said bag having a mouth and said frame being formed to provide means for securing the bag mouth closed, a pouch of water proof material designed to receive said purse, and said pouch having an air bag connected thereto to make the carrier non-sinkable.
- 30 5. A fisherman's leader carrier, comprising a purse consisting of a frame and a bag of moisture retaining material secured therein, a water-proof pouch designed to receive the purse, and means connected to the structure for making the same non-sinkable.
- 35 6. A fisherman's leader carrier, comprising a purse consisting of a frame and a bag of moisture retaining material secured therein, a water-proof pouch designed to receive the purse, and means carried by the pouch for making the carrier non-sinkable.
- 40 7. A fisherman's leader carrier, comprising a purse consisting of a frame and a bag of moisture retaining material secured therein, and a water-proof pouch designed to receive the purse.
- 45 8. In testimony whereof I hereunto affix my signature.

SHERMAN O. HUFFMAN.
